UNITED STATES PATENT OFFICE.

GOTTFRIED BAUMANN, OF HEATON MERSEY, ENGLAND.

CYCLE-LOCK.

1,137,691.

Specification of Letters Patent. Patented Apr. 27, 1915.

Application filed September 18, 1912. Serial No. 721,064.

To all whom it may concern:

Be it known that I, GOTTFRIED BAUMANN, subject of the King of Great Britain, residing at Rutli Villa, Mersey Road, Heaton Mersey, in the county of Lancaster, England, have invented certain new and useful Improvements in Cycle-Locks, of which the following is a specification.

The present invention relates to new and useful improvements in cycle locks and more particularly to that type of lock disclosed in my British Patent No. 14,091, granted to me the 2nd of May 1912, and the object of my invention in general is to so improve the construction of the lock therein set forth that it may be more cheaply and durably constructed.

A further object of my invention is to provide means for holding the numbered or lettered locking rings against casual rotation. And a still further object of my invention is to so construct the body or casing of the lock as to absolutely prevent the taking apart of the lock when in use and the consequent unlocking of the cycle.

With these and other objects in view, my invention will be more fully described, illustrated in the accompanying drawings, and then specifically pointed out in the claim which is attached to and forms a part of this application.

In the drawings: Figure 1 is an elevation, partially in section, showing my improved lock in use; Fig. 2 is a central longitudinal sectional view of the lock, showing the position of the parts when unlocked, the rings being turned to such a position that the locking pin may be extended; Fig. 3 is a transverse sectional view on the line 3—3 of Fig. 2; Fig. 4 is a detail perspective view of the spring washer employed in holding the locking rings against casual rotation; Fig. 5 is an elevation, partially in section, showing the application of a modified form of lock; Fig. 6 is a longitudinal sectional view, similar to that of Fig. 2, but showing a modified form of construction; Fig. 7 is a detail, fragmentary longitudinal section, showing an adjustable type of locking ring which may be employed with my lock; Fig. 8 is an unassembled perspective view of the type of locking ring shown in Fig. 7; Fig. 9 is a fragmentary longitudinal sectional view of a still further modified form of lock.

Corresponding and like parts are referred to in the following description and indi-

cated in all the views of the drawings by the same reference characters.

My improved lock is of that type in which the body member of the lock is passed between the spokes of one of the cycle wheels, preferably at a point adjacent the rim thereof, and in which the ends of the lock, when in operative position, are seated in or otherwise engaged by the forks of the cycle frame, the wheel being thereby held against rotation.

The lock proper includes a tubular bushing 10 provided intermediate its length with a longitudinally extending slot 11 and with one end externally threaded as shown at 12. Mounted upon the unthreaded end of this bushing, is a sleeve 13 which is held in place by a bolt 14, the tapered end 15 of which is driven into the end of the bushing expanding the same against the inner face of the sleeve to lock the sleeve and bushing against independent movement. The inner end of this sleeve is also provided with a longitudinally extending slot 16 which registers with one end of the slot 11 and slidably mounted in the bushing, is a locking bolt 17 which, in its innermost position, extends but slightly beyond the threaded end of the bushing. A pin 18 is passed through the registering slots 16 and 11 and threaded or otherwise secured by its inner end into the inner end portion of the bolt 17, this pin providing for manually extending and retracting the locking bolt 17 beyond the bushing. This locking bolt is further provided with a plurality of spaced locking pins 19 which are in alinement with each other and with the pin 18 but which are so proportioned as to extend but a slight distance through the slot 11.

Mounted for rotation about the bushing 10 and bearing against each other and against the inner end of the sleeve 13, are a plurality of locking rings 20, each of which is provided with a radially extending slot 21 through which the pins 19 may pass when the locking rings are positioned to bring said slots in registration with the slot 11 of the bushing. These locking rings are also provided in their outer faces with annular recesses 22 in which the pins seat both when the bolt is in active and normal positions, these recesses permitting the free rotation of the locking rings to bring their radial slots out of alinement with the slot 11 of the bushing.

Surrounding the bushing and bearing against the outermost of these rings 20, is a spring washer 23 which, as best shown in Fig. 4 of the drawings, is slotted to provide a tongue 24 which is bent outwardly at right angles to the body member and a radial slot 25 which registers with the slot 11 of the bushing. A second sleeve 26 is internally threaded to engage with the threads 12 of the bushing and is screwed upon the bushing as shown in Fig. 2 to bear closely by its inner end against the outer face of the washer 23. The inner end of this second sleeve is provided with a radially extending recess 27 in which the tongue 24 seats when the sleeve is in place.

Each of the locking rings 20 is preferably provided at its inner end with a radially extending milled flange 28 by means of which it may be readily turned and each ring is marked about its periphery with a series of letters or numbers as shown at 29 in Fig. 1 of the drawings, one of these letters in each instance being directly over the outer end of the slot 21.

In order to provide for a clear understanding of the application and operation of my improved lock, I have illustrated the same in use, 30 indicating one of the forks of the cycle frame and 31 one of the wheels having the usual spokes 32. The inner faces of the prongs of the fork are provided with openings 33 through which the locking bolts 14 and 17 may be passed, the prongs about these openings being preferably strengthened by brazing plates of sheet metal 34 upon the prongs and about the openings.

In applying the lock, the locking rings 20 are turned in such a manner as to bring their radial slots 21 in alinement with the slot 11 of the bushing, this being readily accomplished by the owner who knows the letter directly over the slot of each of the locking rings by revolving the rings until these letters are brought in alinement with the extended end of the pin 18. The lock is then positioned between adjacent spokes 32 of the wheel with the locking bolt 14 inserted through the opening 33 of one of the prongs and swung into alinement with the opening in the opposite prong. The locking bolt 17 is then moved to extended position to pass its free end through the opening of the other prong and so lock the wheel 32 of the wheel with the locking bolt 14 against rotation. When this is done, the outermost of the pins 19 is seated in the radial recess 27 of the sleeve 26, while the remaining of said pins are seated in the annular recesses 22 of the locking rings. 60 Certain or all of the locking rings are then turned to bring their radial slots 21 out of registration with the slot 11. When this is done, it will be apparent that the locking bolt 17 is securely held in extended position and cannot be retracted until the lock-

ing rings are returned to the position shown in Fig. 2. As there are a plurality of these rings and as the letters are differently arranged upon each of the rings, it will be readily seen that it would be almost impossible for a person not acquainted with the lock to unlock the same.

The seating of the outermost of the pins 19 in the recess 27 of the sleeve prevents the partial unthreading of the sleeve from the bushing when the lock is in use, even though the ends of the sleeves 13 and 26 do not bear snugly against the inner faces of the fork prongs. This is of great importance as otherwise the sleeve 26 might be partially unthreaded, allowing slight longitudinal movement of the locking rings, thereby greatly assisting in the unlawful releasing of the lock.

The spring washer 23 being compressed between the sleeve 26 and the outermost of the locking rings serves to maintain the locking rings in frictional engagement with each other and with the sleeve 13 and therefore to prevent their casual turning out of position during the application of the lock.

In Figs. 5 and 6, I have illustrated a slightly modified form of lock in which the operating parts are essentially the same and have shown its application to the frame of a cycle. In this case, the sleeve 13 and also the bolt 14 are replaced by a solid cylindrical head 35 formed upon one end of the bushing 10 and provided with a socket 36 formed in its free end.

The locking bolt 17 is replaced by a locking bolt 38, the outer end of which is enlarged to provide a head 39 having a socket 40. When this type of lock is employed, the prongs of the fork 30, instead of being provided with openings, are provided with oppositely formed inwardly directed studs 41 adapted to seat in the sockets 36 and 40 of the lock. With the exception of the above differences, this form of lock is identical in construction with that previously described and its operation is consequently the same.

If preferred, the sleeve 13 may be retained and the bolt 14 replaced by a bolt 42 as shown in Fig. 9 of the drawings, this bolt having a tapered end 43 which is inserted in the end of the bushing and having at its free end a head 44 provided with a socket 45.

In order to insure further protection against unauthorized releasing of the lock, I prefer to employ locking rings of the type disclosed in Figs. 7 and 8 of the drawings. The rings shown in the other figures are of a different and simpler form in order to avoid unduly complicating the drawings, but it will be understood that rings of the type shown in Figs. 7 and 8 may be employed in their place without in any way

departing from the spirit of my invention. These latter rings each include an outer tubular casing 46 provided at one end with a milled flange 47, similar to that of the rings 5 30 and having a tapped bore 48 adapted to receive a binding pin 49. They further include an inner ring 50 provided with a radially disposed slot 51 which, in assembled position of the ring, takes the place of the 10 radial slot 21 of the locking rings 20, as shown in Fig. 7. This inner ring is provided about its peripheral face with a plurality of longitudinally extending grooves or recesses 52 adapted to receive the inner 15 extended end of the set pin 49 to lock the inner ring against rotation with respect to the outer ring. The inner ring is considerably shorter than the outer ring and is secured within the outer ring with one end 20 flush with the flanged end of the outer ring to provide, when the rings are assembled, an annular recess 53 corresponding to the recesses 22 of the rings 20. The outer ring is marked about its periphery with a series 25 of letters or numbers in the same manner as are the rings 20 and it will be apparent that by removing the set pin 49, the inner ring may be turned to bring its slot 51 in alinement with any desired letter or number 30 carried by the outer ring, the rings being then again secured together by replacement of the set pin which is of such length as to not only seat in the grooves 52, but to bear against the inner faces thereof and so prevent 35 independent longitudinal movement of the rings. When rings of this type are employed, it will be apparent that by retracting the locking bolt 17 or the locking bolt 38, as the case may be, to seat the pins 19 40 in the annular recesses of the rings, the sleeve 26 may be unthreaded from the bushing and the lock taken apart, permitting the removal of the locking rings. These locking rings may be then adjusted and replaced 45 and the sleeve again applied to the bushing. By this means, the owner of the lock can at any time change the combination of let-

ters or numbers necessary to unlock the same, thus avoiding the necessity of getting a new lock in case the combination of 50 the old lock is discovered.

From the foregoing description, it will be apparent that I have made a number of improvements over my old lock among which is the provision of the spring washer 55 23 for holding the locking rings against casual rotation. Another improvement consists in the provision of the radial recess 27 in the sleeve 26 arranged to receive one of the pins carried by the locking bolt and so 60 prevent the unthreading of the sleeve 26 when the lock is in use.

Having thus described the invention, what is claimed as new is:

A lock including a tubular bushing provided with a longitudinal slot, a fixed bolt mounted in one end of the bushing, a second bolt slidably mounted in the bushing and adapted in active position to be extended beyond the other end of the same, a plurality 65 of spaced pins carried by said second bolt and extending through the slot of the bushing, a plurality of locking rings rotatably mounted upon the bushing and provided with radial slots for the passage of the pins 70 75 of the locking bolt and in one face with an annular recess, a sleeve threaded upon that end of the bushing through which the movable bolt extends and having its inner end recessed to register with the slot of the 80 bushing, and a spring washer mounted between the inner end of the sleeve and the outer locking ring, said washer having a radially formed outwardly bent tongue seating in the recess of the sleeve and providing 85 a slot registering with the slot of the bushing.

In testimony whereof I affix my signature in presence of two witnesses.

GOTTFRIED BAUMANN.
